United States Patent Office

Des. 179,032
Patented Oct. 23, 1956

179,032

COURTESY BATTERY CHECK TESTER

Adlai C. Peth, Phoenix, Ariz.

Application July 28, 1955, Serial No. 37,197

Term of patent 14 years

(Cl. D52—1)

Fig. 1

Fig. 3

Fig. 2

Fig. 4

Fig. 1 is a front perspective view of a courtesy battery check tester showing my new design.

Fig. 2 is a rear elevation of the tester shown in Fig. 1.

Fig. 3 is a plan view of the tester shown in Fig. 2.

Fig. 4 is a right hand side elevation of the tester shown in Fig. 2.

I claim:

The ornamental design for a courtesy battery check tester, as shown.
